United States Patent Office.

CHARLES PETERSON AND CHARLES GUNNER, OF SAN FRANCISCO, CALIFORNIA.

Letters Patent No. 70,854, dated October 29, 1867.

IMPROVED BOAT-DETACHING TACKLE.

The Schedule referred to in these Letters Patent and making part of the same.

TO ALL WHOM IT MAY CONCERN:

Be it known that we, CHARLES PETERSON and CHARLES GUNNER, both of the city and county of San Francisco, and State of California, have invented new and useful improvements in Boat-Detaching Devices; and we do hereby declare the following to be a full and correct description of the same, sufficient to enable others skilled in the art to which our invention appertains to fully understand and use the same, reference being had to the accompanying drawings, which make part of this specification, and in which—

Figure 1 is a plan view of a boat provided with our detaching device.

Figure 2 is a longitudinal vertical of the same in line $x\ x$, fig. 1.

Figure 3 is a transverse vertical section of the same in line $y\ y$, fig. 2; and

Figures 4 and 5 are detached views of parts of the detaching device.

Similar letters of reference indicate corresponding parts in the several figures.

The nature of our invention consists in a novel device, operated by a lever from one of the thwarts of the boat, by means of which the blocks of the fore and the aft tackle, on which the boat hangs, are simultaneously detached from the boat.

A, in our drawings, represents the bow, and A' the stern of a boat, to which short rods B B' are pivoted, which, when hanging downward, rest in the loops c, which are bent at right angles to the rods C, of which they form part. These rods are fastened in the keel of the boat, and are, when necessary, as in this case the after one, held near the bottom of the boat by a bolt or bolts, α . Up and down on the rods C slide sleeves or tubes D D', in such a manner that when the rods B B' are resting in the loops c, and the sleeves D are slid up on the rods C, they will also slide over the rods B B', and securely hold them in the loops c. E represents a thwart in the boat, which may be entirely slotted, or be provided with a slot in its centre only, in which a drum or roller, e, is pivoted, having a lever, f, attached to it. A rope, b, is attached, with one end to the lever f, and, passing over the roller e, towards the starboard side, is led downward, and then through an eye-bolt along the bottom of the boat towards the stern, when, after passing through eye-bolts g and h, it is secured by a number of half hitches to the sleeve D, and passes back, through eye-bolts g and i, over the port side of the roller e, and is fastened to the lever f. A second rope, d, is fastened to the lever f, passed through eye-bolts secured to the sleeve D', and returned to the lever f in a similar manner, the number of eye-bolts through which the rope passes being determined as necessity requires. Thus, when the lever is forced over to the starboard side, the starboard parts of the ropes b d will be slackened while the port parts are pulled, drawing the sleeves D D' respectively downward from over the rods B B', leaving them free to be raised out of the loops. When the lever is then pulled over to port, the rods B B' being placed down into the loops c, the port ropes are slackened and the starboard parts pulled, which draws the sleeves D D' up on the rods C and over the rods B B'. In fig. 2 the boat is represented as hanging by the tackles from the davits, the hooks of the blocks being slipped over the rods B B', which lie in the loops c, and are held by the sleeves D D', the lever f being to port. The whole boat's crew, or but one man, as the case may be, being seated in the boat, the same can now be detached instantaneously by simply moving the lever from port to starboard.

In detaching boats when a high sea is running, it is especially necessary to detach them at the moment when the water has touched the boat, rising from below and elevating it a little before receding; for if it should be detached before the water has reached it, its weight, and the force of its fall acting against the force of the rising wave, would in a great many cases stave the bottom of the boat in. As soon as the man in charge of detaching the boat feels the water touching the boat, he throws the lever from starboard to port, thereby pulling the sleeves D D' down from over the rods B B', the boat-tackles being at the same time slack, and their hooks not pulling on the rods B B'. As soon as the wave recedes, taking with it the boat, the tackles are tautened and lift the rods B B', the hooks of the tackle-blocks slip from over them, and the boat is free.

In many of the numerous boat-detaching devices, their efficiency is destroyed by either great bulk or such position that the utmost care is required by the boat's crew not to accidentally interfere with their operation. In such moments of danger, when a boat is detached in a high sea, each man must be fully alive to his duty, as much depends on his presence of mind and skill in handling his oar. His attention ought not, therefore, to

be divided by the possibility of his accidentally entangling the detaching device. Our device being placed on the bottom of the boat, under the bottom boards, is entirely out of the way, enabling the men to move their feet about without danger of interfering with the detaching device. The hooks of the tackles may either be moused, or may be formed of a ring, as may be found best. The roller *e* may be pivoted in a slot in any of the thwarts, or in a board secured in the boat for that especial purpose, the lever *f*, when either to starboard or port, lying in notches *k* in the thwart or board, and being held down by a cross-bolt or any other suitable means. Instead of the eye-bolts, and to facilitate the operating of the ropes, we may use clamps provided with rollers, but we do not wish to restrict ourselves to any particular manner of guiding the ropes. We do not confine ourselves to the use of ropes, but may use chains, metal rods, or any other suitable means.

Having thus described our invention, what we claim as new therein, and desire to secure by Letters Patent, is—

1. The rods *C*, attached to the bottom of a boat, their upper ends being free, and provided with loops *a* substantially as and for the purposes described.
2. The sleeves *D D'* on the rods *C*, substantially as and for the purposes described.
3. The rods *B B'*, pivoted as described, in combination with the rods *C* and sleeves *D D'*, and ropes *b* and *d*.
4. The roller or drum *e*, pivoted in a slot in a thwart or cross-board, and provided with a lever, *f*, substantially as and for the purposes described.
5. The detaching device, consisting of the rods *B B'* and *C*, sleeves *D D'*, ropes *b* and *d*, and roller or drum *e*, provided with a lever, *f*, and pivoted in a slotted thwart or board, substantially as described.

CHARLES PETERSON,
CHARLES GUNNER.
